RALPH A. PEATMAN, OF MOUND CITY, KANSAS.

PUMP ATTACHMENT FOR AUTOMOBILES.

1,336,920.

Specification of Letters Patent. Patented Apr. 13, 1920.

Application filed September 8, 1919. Serial No. 322,451.

To all whom it may concern:

Be it known that I, RALPH A. PEATMAN, a citizen of the United States, residing at Mound City, in the county of Linn and 5 State of Kansas, have invented certain new and useful Improvements in Pump Attachments for Automobiles, of which the following is a specification.

This invention relates to pumping attachments for automobiles, and more especially to an attachment for pumping water. The object of the invention is to produce a simple, strong, durable, inexpensive and efficient device which can be easily and 15 quickly secured in or removed from position without the use of any special tools or skilled service.

With this general object in view the invention consists in certain novel and useful 20 features of construction and organization of parts as hereinafter described and claimed; and in order that it may be fully understood, reference is to be had to the accompanying drawing, in which:

25 Figure 1, is a fragmental side view of a motor car equipped with a pumping attachment embodying my invention.

Fig. 2, is a plan view of the construction shown by Fig. 1, with part of the running 30 board and the fender of the adjacent wheel omitted.

Fig. 3, is an enlarged detail perspective view to disclose features not clearly shown in the other figures.

35 In the said drawing, where like reference characters identify corresponding parts, 1 is a running board, 2 the corresponding fender, and 3 one of the rear or driving wheels of a motor car, which wheel for the 40 operation of the pump, will be jacked up so that the full power of the engine shall be utilized in the operation of the pump.

The pumping attachment is constructed as follows: 4 designates a pair of rods which 45 are preferably tubular and curve downward at their rear ends as at 5 and terminate in bearing sleeves 6 for a shaft 7. The shaft between the bearing sleeves is equipped with a friction wheel 8 and beyond the outermost bearing sleeve with a crank arm 9 pivotally connected by a link 10 with the piston rod 11 of a pump 12. The pump is disposed in longitudinal alinement with the axis of shaft 7 and is secured firmly in eyes 55 13 formed at the outer ends of a pair of cross bars 14 clamped rigidly to the rods

4 by fastening devices 15 comprising U-shaped bolts and nuts or any equivalent means, the said rods 4 and cross bars 14 constituting a rigid skeleton pump and 60 drive pulley supporting frame. Mounted on the front end of the pump is a T-coupling 16 provided with a supply pipe 17 and a discharge pipe 18, the pipe 17 being equipped with a check valve 19 adapted to 65 open on the suction stroke of the piston stem and close on the reverse stroke thereof. The discharge pipe 18 is equipped with a similar check valve 20 which closes on the suction stroke of the piston stem and 70 opens on the reverse stroke thereof.

For securing the pumping mechanism described to the car, a pair of transversely extending clips 21 capable of being fitted onto the running board from the outer edge 75 thereof, are slidingly secured by depending U-bolts 22 to the rods 4 of the skeleton frame, and said clips each carry one or more clamping screws 23 operable from below and adapted to impinge against the underside of 80 the running board. For longitudinal adjustment of the pumping mechanism with respect to said clips for the purpose of securing the friction pulley tightly against the wheel 3 (to be jacked up as explained), 85 the foremost cross bar 14 is equipped centrally with an upwardly projecting post 24 for engagement by a concave presser foot 25 swiveled on the rear end of a clamping screw 26 mounted in a bearing bracket 27 90 secured to the underside of the foremost clip 21, as shown clearly in Fig. 3.

Assuming that the attachment is fitted on the running board of the car and that the proper wheel thereof is jacked up, the operator first clamps the foremost clip 21 firmly to the running board by means of its clamping screws 23. He then turns the clamping screw 26 to apply pressure on the post 24 and thus force the pump and drive 100 pulley carrying frame rearwardly until the pulley is firmly engaged with the wheel. He then clamps the rearmost clip firmly to the running board. It is preferred to effect the adjustment as explained, although it is obvious that if the rods 4 slide freely through the U-shaped bolts 22, both clips may be initially clamped firmly to the running board. The pipe 17 being then connected to the water supply, the engine will be started and 105 will effect a continuous discharge of water through the discharge pipe 18 for washing

the car or for any other purpose, as it has been found in practice that water can be discharged with great force and for a considerable distance by means of this attachment.

To remove the attachment it is simply necessary to loosen the clamping screws 23, when the attachment can be slipped off the running board.

10 From the above description it will be apparent that I have produced a pumping attachment for automobiles which embodies the features of advantage set forth as desirable in the statement of the object of the 15 invention and while I have illustrated and described the preferred embodiment of the invention, it is obvious that it is susceptible of change in minor particulars without departing from the spirit and scope of the 20 appended claims.

I claim:—

1. A pumping attachment for automobiles comprising a skeleton frame, a friction pulley journaled thereon, and at the rear end of 25 said frame, a reciprocatory pump carried by said frame at one side thereof, and connected to the pulley to be operated thereby, a pair of clips above and transversely arranged as regards the pump, slidably carrying the said frame and provided at the 30 same side of the frame as the pump, with upstanding hooks for fitting over the outer

edge of a running board of the automobile, means to clamp one of said clips firmly to the running board, and coöperating means 35 carried by the last named clip and the skeleton frame, for effecting longitudinal adjustment of said frame to press the friction wheel firmly against a wheel of the automobile. 40

2. A pumping attachment for automobiles comprising a plurality of clips to be fitted upon a running board of the automobile from the outer edge of said running board, means to clamp said clips firmly in place, a 45 skeleton frame embodying a pair of parallel rods slidably supported by and below said clips, a shaft journaled on the rear ends of said rods, a drive pulley secured on said shaft for engagement with the adjacent 50 drive wheel of the car, a crank secured upon the outer end of said shaft, a pump carried by said slideable frame beyond the plane of the outer edge of the running board, a link pivotally connecting the said crank with the 55 piston rod of the pump, supply and discharge pipes connected to the front end of the pump, check valves mounted in said pipes to direct the flow of the fluid, and means carried by the foremost clip for forcing the slideable frame rearward and holding it in the desired point of adjustment. 60

In testimony whereof I affix my signature.
RALPH A. PEATMAN.
